BY Walton Harrison,
ATTORNEY.

UNITED STATES PATENT OFFICE.

JOSEPH KALLMAN STRAUS, OF JAMAICA, NEW YORK, ASSIGNOR TO THE ULLMAN MANUFACTURING COMPANY, OF LONG ISLAND CITY, NEW YORK, A CORPORATION OF WEST VIRGINIA.

FRAME FOR PHOTOGRAPHS, DISPLAY CARDS, AND THE LIKE.

Application filed December 21, 1926. Serial No. 156,078.

My invention relates to frames for photographs, display cards and the like, my more particular purpose being to improve the efficiency of the frame and to facilitate its manufacture as well as to improve its appearance.

Reference is made to the accompanying drawing forming a part of this specification, and in which like reference characters indicate like parts throughout the several figures.

Figure 1 is a rear view, partly in elevation and partly showing portions of the frame as broken away.

Figure 2 is an inverted plan, or bottom view, of my improved frame complete.

Figure 3 is a cross section through one of the frame pieces, made in this instance of wood.

Figure 4 is a section somewhat like Figure 3, but showing the frame piece in its condition when the frame is partially finished and contains the glass pane.

Figure 5 is a section on the line 5—5 of Figure 1, looking in the direction indicated by the arrows, and showing the frame as completed, all parts being in position.

Four frame pieces, 6, 7, 8 and 9, made preferably of wood, are mitered and fitted together so as to form a rectangular frame. Slidably fitted into this frame is a back plate 10, carrying an easel brace 11, and a limiting strap 12 extending from this easel brace to the back plate.

The easel brace 11 has preferably the form indicated in Figures 1 and 2, and the limiting strap 12 determines the position of the easel brace when swung out at the bottom so as to support the frame in inclined position.

The frame is provided with a slot 13 in which the back plate 10 is adapted to fit slidably.

The frame is further provided with a projecting flange 14, of the form indicated in Figures 3, 4 and 5, the top surface of the flange according to the three figures just mentioned being indicated at 15. The frame is further provided with an inner surface 16, at right angles with the surface 15.

The slot 13 is bounded in part by a flat surface 17.

A glass pane is shown at 18, and serves generally in the manner well known in this art for protecting the picture 19. Instead of this picture, a display card, photograph or the like may be used.

Mounted upon each frame piece such as 6 is a covering 20 made of flexible sheet material, such as thin leather or leatheroid, held in position by an adhesive, such as a very thin coating of glue, not shown. The covering 20 is provided with portions 21 and 22 bent partially around the flange 14 and made to adhere to the adjacent surfaces 65 thereof, and particularly to the surface 15. This covering also partially covers the upper surface of the frame piece, according to Figure 4, and for this purpose the portion 23 of the covering is made sufficiently narrow not to reach entirely across the top of the frame piece, as may be understood from Figure 4.

A binding strip 24, shown more particularly in Figures 4 and 5, and made in this instance of cloth, is glued or pasted down, as indicated in Figure 4, so that a portion 25 of this cloth strip overlaps the adjacent portion 23 of the covering 20. The cloth strip 24 is provided with a portion 27, which is bent or forced down, as indicated in the figure last mentioned, so as for the time being to close the slot 13. The cloth strip is further provided with a narrow portion 28, which extends laterally inward, at a right angle to the portion 27 and is caused to adhere directly to the adjacent edge portion of the glass 18 or of the picture 19 in contact therewith.

When the frame, during its manufacture, reaches this stage, namely when the portion 27 of the binding strip 24 completely covers the slot 13, as indicated in Figure 4, the operator takes a sharp knife, thrusts it through the portion 27 and into the slot 13, and then by drawing the knife along endwise of the slot, splits the portion 27 from end to end of the slot 13, and this means of course throughout that portion of the frame constituted by the frame pieces 6, 7 and 8. The two edges thus left loose and overhanging the slot 13, are next tucked down into the slot, as indicated at 29 and 30, in Figure 5, and made to adhere to the adjacent bound-

ing surfaces of the slot 13, as indicated in Figure 5.

The back plate 10 is next slidably fitted into position, as indicated in Figure 5.

5 An important feature of my invention is the one illustrated more particularly in Figures 4 and 5, namely, that a portion of binding strip, first covering the slot 15, is split and the edges tucked down into the slot and 10 there secured, and afterward held firmly in position by pressure of the back plate 10.

The inwardly tucked edge portions 26 and 30 of the binding strip not only strengthen the frame, but serve to cushion the back 15 plate 10; to prevent lost motion between this back plate and the frame, and thus to prevent any rattling movement between these parts; to improve the appearance of the frame, by avoiding rough edges upon the 20 binding strip, and particularly where it bound the slot 13.

In practice, the frame is assembled as follows: First, the four frame pieces 6, 7, 8, 9, 25 are brought together, and upon each of the frame pieces is placed the covering 20, and upon the frame pieces 6, 7, and 8 are placed the binding strips 24, as above described. Second, the glass pane 18 is placed in position, as indicated in Figures 4 and 5, so that 30 its edge portion rests upon the edge portion 22 of the covering, so as to hold the same firmly in position. Then the picture 19 or its equivalent, such as a photograph or a display card, is placed in position, the edge portion 28 of the binding strip 24 being brought down upon the adjacent portion of the glass pane. Next the portion 27 of the binding strip 24 is split as above described, and its edges 26 and 30 tucked into the slot 35 40 13, as indicated in Figure 5. Finally the back plate 10 is slidably fitted into position, between the edges 26 and 30, and reaching out into the slot 13.

The frame constructed as above described 45 is very strong, presents a neat appearance, and holds the photograph or its equivalent firmly in position, and yet so as to be accessible by removing the back plate 10.

To use the frame, it is placed upon a table, 50 mantel board or other suitable support, the easel brace 11 is swung outwardly to the limit permitted by the strap 12, and the frame as a whole and its accompanying parts thus serve practically as an easel.

55 I do not limit myself to the precise mechanism shown and described, as variations may be made therein without departing from my invention, which is commensurate with my claims.

60 Having thus described my invention, what

I claim as new and desire to secure by Letters Patent is as follows:

1. A device of the character described comprising a frame piece provided with a projecting flange and further provided with a slot, a covering carried by said frame piece and provided with a portion bent partially around said flange, and a binding strip secured to said covering and to said frame piece, said binding strip being provided with a portion extending into said slot.

2. In a frame of the character described the combination of a frame member provided with a flange and with a slot, a covering of sheet material carried by said frame member and provided with a portion bent partially around said flange, a binding strip carried by said frame member and engaging said covering, said binding strip being tucked partially into said slot, a glass pane 80 engaging said portion of said covering which is bent partially around said flange, and a member of sheet material connected with said glass pane and extending therefrom into said slot.

3. A device of the character described comprising a rectangular frame made up of frame members, each provided with a projecting flange, a covering of sheet material carried by each frame member and provided with a portion bent partially around the flange thereof, a pane of transparent material carried by said rectangular frame and engaging said covering where it bends partially around said flange, a member of sheet material engaging said pane of transparent material and extending therefrom into said slot, a binding strip overlapping one edge of said covering and carried by said frame member, said binding strip extending into said slot and thus brought opposite said strip of sheet material extending into said slot, and a back plate carried by said frame and slidably extending into said slot so as to engage both said strip of sheet material and the edge portion of said binding strip.

4. A frame of the character described made of frame pieces fitted together in the proximate form of a rectangle, each of said frame pieces being provided with a slot, covering members of sheet material carried by said frame members and provided with portions extending into said slot, and a back plate carried by said frame and extending into said slot, so as to engage said covering members extending thereinto.

Signed at Jamaica, in the county of Queens and State of New York, this 16th day of December, 1926.

JOSEPH KALLMAN STRAUS.
